UNITED STATES PATENT OFFICE

100,197

DESIGN FOR AN EMBOSSED HOT DISH MAT OR SIMILAR ARTICLE

Nelson C. Brewer, Chicago, Ill., assignor to Chas.
A. Brewer & Sons, Chicago, Ill.

Application April 9, 1936, Serial No. 62,022

Term of patent 3½ years

To all whom it may concern:

Be it known that I, Nelson C. Brewer, a citizen of the United States, residing at Chicago, in the county of Cook and State of Illinois, have invented a new, original, and ornamental Design for an Embossed Hot Dish Mat, or Similar Article, of which the following is a specification, reference being had to the accompanying drawing, forming part thereof.

I claim:

The ornamental design for an embossed hot dish mat, or similar article, as shown.

NELSON C. BREWER.
